UNITED STATES PATENT OFFICE.

JERRY E. GREGG, OF CLOUDCROFT, NEW MEXICO.

PUMP.

1,172,789.

Specification of Letters Patent. Patented Feb. 22, 1916.

Application filed February 6, 1915. Serial No. 6,886.

To all whom it may concern:

Be it known that I, JERRY E. GREGG, a citizen of the United States, residing at Cloudcroft, in the county of Otero and State of New Mexico, have invented certain new and useful Improvements in Pumps, of which the following is a specification, reference being had to the accompanying drawings.

10 This invention relates to pumps and more particularly to a valved pump of the plunger type.

The present invention has for its primary object to provide a pump of the above character so constructed that the power necessary to operate the same may be reduced to a minimum, it being necessary to overcome only the actual weight of the water plus the friction of such machinery, as is 20 used in the operation of the pump, in order to lift the water and discharge the same from the well or reservoir.

It is a further object of my invention to provide an improved construction and arrangement of the pump valves whereby they may be readily assembled and connected to the lower end of the pump barrel and lowered into the well, and a seat or support connected to the lower end of the well casing 30 upon which the valve mechanism normally rests and is supported, whereby said mechanism may be bodily removed from the casing for the purpose of repair, without necessitating the removal of said casing.

35 It is an additional object of my invention to produce a very efficient, durable and serviceable pump mechanism which may be manufactured and sold at comparatively small cost.

40 With the above and other objects in view, my invention consists in the novel features of construction, combination, and arrangement of parts to be hereinafter more fully described, claimed, and illustrated in the 45 accompanying drawing, in which,

Figure 1 is a vertical section through the lower end of the well casing, showing my improved pump valve mechanism arranged therein and the lower valve in open position; Fig. 2 is a similar view, the lower valve being closed and the upper valve open; Fig. 3 is a section taken on the line 3-3 of Fig. 1 and Fig. 4 is a section taken on the line 4-4 of Fig. 1.

55 Referring in detail to the drawing, 5 designates the well casing which is pref-

erably constructed of sheet metal and is provided upon its lower end with exterior screw threads. A relatively thick metal sleeve 6 is also provided with exterior screw threads 7 on its upper end and extends below the well casing to constitute and effect a continuation thereof. This sleeve is connected to the threaded lower end of the casing 5 by means of an interiorly threaded collar 8. It will thus be seen that the upper end of the sleeve 6 produces an annular inwardly projecting shoulder or seat 9 at the lower end of the casing 5.

A pipe or tube 10 is adapted to be coupled or connected in any approved manner at its upper end to the pump barrel, (not shown). Through this tube and the pump barrel, the piston rod 11 extends, and the lower end of said rod is equipped with a 75 piston 12 which snugly fits within the pipe or tube 10 for reciprocatory movement. The internal diameter of the pipe 10 at its lower end, is reduced, and such reduced portion provided with interior screw threads indicated at 13.

A cylinder 15 is adapted to snugly fit within the sleeve 6, and the upper end of this cylinder is diametrically enlarged, as indicated at 16, and the lower end of such enlarged portion is adapted to seat upon the shoulder 9 at the upper end of the sleeve 6. A packing ring, indicated at 17, is preferably interposed between the abutting ends of the cylinder enlargement 16 and the sleeve 6 to provide a substantially fluid-tight joint. The enlarged end 16 of the cylinder 15 is also interiorly threaded, as at 18, to receive the exteriorly threaded valve casing 19. This valve casing includes an outer cylindrical body wall and an inner cylindrical wall 20 which is arranged in spaced concentric relation to said outer wall and is extended beyond one end of the valve casing in the form of a pipe or tube 21. The extremity of this tubular extension of the valve casing is exteriorly threaded for engagement with the interior threads on the pipe or tube 10, as clearly shown in Fig. 1, and the outer and inner cylindrical walls 19 and 20 of the valve casing are integrally connected by the longitudinally extending webs 22 which are disposed in radial relation to the axis of the casing. Upon the tubular extension 21 of the valve casing, the valve member 23 is loosely engaged and is adapted to freely move upon said extension between

the upper end of the valve casing and the lower end of the pipe 10. This valve member, when in its normal position, extends over the webs 22 and rests upon the outer 5 wall 19 of the casing, thus closing the upper ends of the spaces between said webs.

The lower end of the body of the cylinder 15 is interiorly threaded to receive the removable valve casing 24 which is of somewhat 10 similar construction to the upper valve casing above described, and includes a central rod or stem 26 which projects upwardly beyond the end of the valve casing and is connected, by means of a series of radially 15 disposed webs 27, to the outer body wall of the casing. The upper end of the stem 26 is threaded to receive a stop nut 28. The valve member 29 is loosely engaged upon said stem for vertical movement between the 20 casing 24 and the bottom face of said nut. This valve member is of somewhat less diameter than the internal diameter of the cylinder 15, so as to permit of the free passage of water upwardly around said valve 25 member when the same is in its open position, as shown in Fig. 1.

In assembling the several parts of my improved pump, the supporting sleeve 6 is first connected to the lower end of the well casing 30 by means of the collar 8, and said support and casing then lowered into the well or reservoir from which the water is to be elevated. After the pipe or tube 10 has been connected to the pump barrel, the extension 21 of the casing of the upper valve 35 is threaded into the lower end of said pipe, the check valve member 23, of course, being first disposed upon the extension 21 of the valve casing. The upper enlarged end of 40 the cylinder 15 is now threaded upon said valve casing. The lower valve casing is then threaded into the lower end of the cylinder, the check valve 29 being properly arranged upon the stem 26. The assemblage 45 of the several parts is now completed, and the pipe or tube 10, together with the pump valve mechanism, which is connected thereto, is lowered into the well casing until the enlarged upper end of the cylinder 15 seats 50 upon the upper end of the supporting sleeve 6 which is connected to the well casing 5. The plunger or piston 12, fastened to the rod 11, is then extended downwardly into the pipe 10 and the pump is in condition 55 for operation. Assuming that the several parts have been thus connected and the valve mechanism lowered into the water and upon the supporting sleeve 6, in the reciprocation of the piston or plunger 10 in its upward 60 stroke, the lower valve member 28 is lifted upon the stem 26 and water is drawn upwardly through the spaces between the webs 27 of the lower valve casing and into the cylinder 15 and the inner tube 21 of the 65 upper valve casing. In the reverse or down-

ward stroke of the plunger 12, water is expelled from the tube 21, and the check valve 29 having returned to its closed position, this water will be forced upwardly through the spaces between the webs 22 of the upper 70 valve casing, thereby lifting the valve member 23 upon the tube 21 until the same engages the lower end of the pipe 10. The water thus passes around said valve member and upwardly through the casing 5 from 75 which it is expelled. By my improved arrangement of the several elements, it will be seen that, in the operation of the pump, all surplus weight and lost motion is overcome, and only sufficient power is necessary 80 to overcome the actual weight of the water and the friction which is a necessary incident to the operation of the pump mechanism. When it is desirable, for any reason, to remove the pump valves from the casing 85 5, this may be easily and quickly done by simply lifting the pump barrel. As the same is drawn upwardly through the casing 5, both of the valves and the cylindrical water receiving chamber 15 are also removed. Thus, it is unnecessary to withdraw the well casing. The several parts 90 can be very easily and quickly assembled or disassembled and replaced at a nominal expense.

From the foregoing description, it will be seen that I have devised a very simple and efficient valved pump which may be employed by farmers and others for the pumping of water for stock, irrigation or other 100 purposes.

It will be apparent that the principle above disclosed may be embodied in pumps of various sizes and capacity. The form, proportion, and arrangement of the several 105 elements employed may also be greatly varied without departing from the essential features or sacrificing any of the advantages of the invention, as embodied in the appended claims.

Having thus fully described my invention, what I desire to claim and secure by Letters Patent is:—

1. In combination, a well casing, a support connected to the lower end of said well casing, upper and lower valves arranged in the well casing, said upper valve including a tubular extension and a valve member loosely engaged upon said extension for vertical movement, and a plunger cylinder connected to said extension whereby the valves and the water chamber may be bodily removed from the well casing, said cylinder constituting a stop to limit the upward movement of the valve member.

2. In combination, a well casing, a support connected to the lower end of said well casing, a water receiving chamber adapted to rest upon said support, upper and lower valves removably mounted in the ends of

said chamber, said upper valve including a central tubular extension and a valve member loosely engaged thereon for vertical movement, and a plunger cylinder detachably connected to said extension whereby the valves and the water chamber may be bodily removed from the casing, said cylinder constituting a stop to limit the upward movement of said valve member.

10 3. In combination, a valve casing, a sleeve connected to the lower end of said casing, the upper end of said sleeve forming an annular seat, a water receiving chamber fitting within said sleeve and resting upon the seat, upper and lower valves removably arranged in the opposite ends of said chamber, and a plunger cylinder detachably connected to the upper valve whereby said valves and the water receiving chamber may be bodily removed from the casing.

15 4. In combination, a valve casing, a sleeve detachably connected to the lower end of said casing, the upper end of said sleeve constituting an annular seat, a water receiving chamber having an enlarged upper end to rest upon said seat, upper and lower valves removably engaged in the opposite ends of said chamber, said upper valve having a central tubular extension projecting above the water chamber, a valve member loosely engaged upon said extension for vertical movement, and a plunger cylinder detachably connected to said extension whereby the valves and the water receiving chamber may be bodily removed from the well

casing, said cylinder constituting a stop to limit the upward movement of said valve member.

5. In combination, a well casing, a water receiving chamber, means on the lower end 40 of said casing to receive and support said chamber, valves removably threaded in the opposite ends of said chamber, each of said valves including a casing having an outer body wall, the lower valve casing being provided with a central guide stem, a valve member loosely engaged upon said stem and normally closing the upper end of the casing, the casing of the upper valve having a cylindrical inner wall extended beyond the upper end of the casing and exteriorly threaded, a plurality of spaced longitudinal webs integrally connecting the inner and outer walls of said valve casing, a valve member loosely engaged upon the extension of the valve casing and normally closing the upper end thereof, and a plunger cylinder detachably connected to said extension and constituting a stop for said valve member, said water receiving chamber and the valves being bodily removed from the well casing when the plunger cylinder is withdrawn.

In testimony whereof I hereunto affix my signature in the presence of two witnesses. 65
